STOP MOTION FOR TERRY WEAVE LOOMS

Eugene Wilson, Cliffside, N.C.

Application January 9, 1958, Serial No. 707,950

6 Claims. (Cl. 139—353)

This invention relates generally to improvements in warp stop motions for terry weave looms and more particularly to an improved apparatus for rendering the stop motion inoperative and slackening the terry warp during the time that the stop motion is rendered inoperative.

In the usual terry weave loom the warp threads are fed from two different beams to form the ground weave and the terry loops. The ground warp is maintained under constant uniform tension while the terry warp is periodically slackened so that the slack warp may be carried forwardly during predetermined beat-up strokes of the lay to form the terry loops. In order to provide a stop motion for the terry warp as well as the ground warp, separate banks of drop wires are provided for the threads of each warp and it is necessary that the bank of terry warp drop wires be rendered inoperative or lifted during the time that the terry warp is slackened in order to prevent a false knock-off of the loom. On the usual terry weave loom the terry warp drop wires are lifted or raised by a bar or the like during each of the terry forming beats of the loom so that they cannot fall and stop the loom when the terry warp is slackened. In the conventional terry weave loom both of these operations, the periodic slackening of the terry warp and the lifting of the bank of terry warp drop wires, are carried out by rotation of a single cam to effect movement to linkage connected to the terry warp slackening apparatus and to the drop wire lifting bar and thus simultaneously effect both these operations.

By using a single cam to control both of these operations, it is impossible to vary the time the terry warp drop wires are rendered inoperative relative to the time that the terry warp threads are slackened, and this is a disadvantage in that it limits the speed at which the loom may be operated and may not be effective when tightly twisted or hard terry warp threads are used. It has also been found that a better terry fabric can be produced with fewer false stops by lengthening the time that the drop wires are rendered inoperative and shortening the length of time that the terry warp is slackened.

With the foregoing in mind, it is the primary object of this invention to provide separate cam means for controlling the slackening of the terry warp and another cam means for raising or lifting the drop wires a short time before, during and after the slackening of the terry warp threads to insure that a false stop will not be effected due to a slackening of the terry warp, rather than because of a broken thread, and to also provide means for easily adjusting the timing relation between the time the terry warp is slackened and the time the terry warp drop wires are rendered inoperative.

It is another object of this invention to provide a novel terry warp slackening actuating cam which is operated more quickly than the conventional type to thereby provide the necessary slack in the terry warp at the precise time the slack is needed to form the terry loops.

It is still another object of this invention to provide a

2

novel terry warp drop wire lifting means which includes an actuating cam, separate and adjustable relative to the terry warp slackening actuating cam, to operate a drop wire lifting plate positioned beneath the terry warp drop wires and which plate is guided for vertical movement in a level manner to insure that the drop wires on each terry thread are raised and lowered equal amounts simultaneously.

Some of the objects of the invention having been stated, other objects will appear as the description proceeds when taken in connection with the accompanying drawings, in which—

Figure 1 is a side elevation of a terry weave loom with parts shown broken away and in section for purposes of clarity;

Figure 2 is an enlarged isometric view of a portion of the terry drop wire lifting plate and associated parts;

Figure 3 is a rear elevation of the loom shown in Figure 1 with the ground warp beam removed and parts

in section;

Figure 4 is a fragmentary sectional plan view taken substantially along the line 4—4 in Figure 3;

Figure 5 is an enlarged vertical sectional view taken substantially along the line 5—5 in Figure 3;

Figure 6 is an enlarged vertical sectional view taken substantially along the line 6—6 in Figure 3;

Figure 7 is an enlarged view of the upper portion of Figure 5 showing the terry warp drop wires in raised or inoperative position.

Referring to the drawings, the loom includes the usual side frames 10 and 11 (Figures 3 and 4), a reciprocable lay 12, and a conventional terry loom reed 13 hingedly mounted on the lay 12. The reed 13 is controlled in a well known manner, not shown, so that the reed is in the rearmost position shown for two beat-up strokes of the lay and then is moved to its forwardmost position on the third beat-up stroke of the lay or the terry loop forming beat-up stroke. The operation of the reed 13 is well known and therefore will not be described in detail.

The lay 12 is reciprocated by rotation of a crank shaft 14 suitably connected by conventional gearing, not shown, to a main drive shaft 15 mounted for rotation in the side frames 10 and 11. The main shaft 15 makes one revolution for each two revolutions of the crank shaft 14 and has a gear 16 fixed thereon which engages the teeth of a mating gear 17 (Figures 3 and 4) fixed on one end of a reed motion shaft 18. The shaft 18 is rotatably mounted in bearing members 20 and 21 (Figure 4) suitably secured to a rear beam 22 by support brackets 23 and 24. The rear beam 22 is fixed at opposite ends on the loom side frames 10 and 11. The gear 17 is one and one-half times as large as the gear 16 on the main shaft and therefore, the reed motion shaft 18 makes one complete revolution with each one and one-half revolutions of the main shaft while the crank shaft 14 makes three revolutions.

The rear of the loom side frames 10 and 11 support a ground warp beam 25 provided with any suitable type of let-off, not shown, to effect the usual tension and hold the ground warp threads relatively tight at all times.

A plurality of ground warp threads indicated at G are fed from the ground warp beam 25, upwardly (Figure 1) and over guide rods 26 and 27, through a broken thread detecting stop motion mechanism indicated broadly at 30, and to the fell of the fabric F. Opposite ends of the guide rods 26 and 27 are suitably supported in respective stop motion support brackets 31 and 32 fixed on the respective side frames 10 and 11 (Figure 3).

The stop motion unit 30 includes opposite end brackets 40 and 41 (Figures 1, 5 and 7). The rods 40 and 41 are bent downwardly at their rear ends and fixed on the

respective stop motion support brackets 31 and 32. The end brackets 35 and 36 support opposite ends of electrical contact bars 43 which are of conventional construction and have two elements insulated from each other. The contact bars 43 are spaced apart from each other and are suitably connected to an electrical circuit, not shown, to operate the stop mechanism of the loom in a conventional manner upon completion of an electrical contact between the two elements of one of the contact bars 43 in a manner to be presently described.

The end brackets 35 and 36 also support opposite ends of drop wire guide bars 45 spaced below and in staggered relation to the contact bars 43 and which serve to confine the drop wires and prevent radial twisting of the wires about the contact bars 43. The drop wires are indicated at 49 and divided into two banks indicated broadly at 50 and 51 for the terry and ground warp threads respectively. Each of the drop wires 49 are identical and are provided with upper slots 52 which are penetrated by the contact bars 43 and thread receiving openings 53 through which the warp threads are passed to normally support the drop wires 49 in substantially the position shown in Figure 7 during normal operation of the loom. Should one of the warp threads become broken, it would no longer support the corresponding drop wire 49 and the drop wire would then drop so that the inwardly projecting portions in the slot 52 would complete an electrical contact between the separate elements of the contact bar 43 and actuate the conventional stop motion mechanism of the loom.

The terry warp threads indicated at T are supplied from a terry warp beam 60 (Figure 1) rotatably supported at opposite ends on the upper rear ends of the frame members 10 and 11. Any suitable let-off may be applied to the terry beam 60 to apply a light tension on the terry threads T and prevent free rotation of the terry beam 60. From the terry beam 60, the terry warp threads T extend downwardly beneath a first feed roll 61 and over a second feed roll 62 which is held against the roll 61 and rotatable therewith when one of the rolls is rotated. One end of the feed roll 62 has a ratchet wheel 63 fixed thereon which is engaged by a ratchet pawl 64 oscillatably mounted on one end of a racking lever 65 adapted to at times rack the wheel 63 and rolls 61, 62 in a manner to be later described.

From the feeding roll 62, the terry warp threads T extend downwardly in Figure 1, beneath a guide rod 66 suitably supported at opposite ends on the side frames 10 and 11, through the stop motion apparatus 30, and to the fell of the fabric F. The terry warp threads T pass through the openings 53 in the forwardmost bank 50 of drop wires 49 to support the same during the time that the terry warp yarns T are held under tension. The parts of the loom heretofore described are conventional parts of the loom and it is in association with these parts that the present invention will be described.

The mechanism for actuating the racking lever 65 includes a control link 70 (Figure 1), the upper end of which is oscillatably connected to one end of the pawl 65 and the lower end of which is oscillatably connected to the outer end of a lever 71. The inner end of the lever 71 is fixed on one end of a rock shaft 72 (Figures 3 and 4) oscillatably mounted in the side frame member 10 and in a bearing member 73 carried by the rear beam 22. The inner end of the shaft 72 has one end of a lever 74 fixed thereon and the other end of which is provided with a roller riding in a cam raceway of a terry motion cam 75. The terry motion cam 75 is suitably secured on the reed motion shaft 18 and the cam raceway has a high portion 75a and a low portion 75b (Figure 1).

Each time the reed motion shaft 18 makes a complete revolution, the control link 70, racking lever 65 and ratchet pawl 64 will move to rotate the rolls 61 and 62 and slacken the terry warp threads T a predetermined

amount. Of course, the length of stroke of the control link 70 and racking pawl 65 may be varied to increase or decrease the amount of slack placed in the terry warp T as desired. The amount of slack in the terry warp T may be varied by adjusting the pivot point at the upper end of the link 70 or the pivot point at the lower end of the link 70 to thus increase or decrease the movement of the pawl 64 with a given stroke being imparted by the cam 75.

As heretofore stated, it is important that the bank of drop wires 50 be prevented from dropping when the terry warp threads T are slackened and to this end, a plate 80 is positioned beneath the bank of drop wires 50 and has a plurality of ribs and grooves indicated at 81 thereon to help prevent turning of the drop wires when they are engaged by the plate 80 in a manner to be presently described. Opposite ends of the plate 80 are mounted for vertical adjustment on the threaded upper ends of respective guide shafts 85 and 86 which are guided for vertical sliding movement in bearing support members 90 and 91. The bearing support members 90 and 91 are suitably secured to the support brackets 31 and 32 respectively carried by the side frame members 10 and 11.

The lower ends of the shafts 85 and 86 have outwardly extending feet 92 and 93 suitably secured thereto and which are at times engaged by respective rollers 94 and 95 fixed on the rear ends of respective lever arms 96 and 97. The other ends of the lever arms 96 and 97 are fixed adjacent opposite ends of a transverse control shaft 100, opposite ends of which are suitably secured in downwardly extending flange portions 102 and 103 of the respective bearing members 90 and 91 (Figure 3). The medial portion of the shaft 100 is rotatably supported in a bearing member 105 (Figures 1 and 3) fixed on the upper end of a support arm 106, the lower end of which is fixed on the support 24 for the bearing member 21 (Figure 4).

The shaft 100 is at times oscillated by a lever arm 107 fixed at its inner end on the shaft 100 and having the upper end of a control link 110 oscillatably attached to its outer end. The lower end of the link 110 is oscillatably mounted as at 111 (Figure 5) intermediate the ends of a control lever 112. One end of the control lever 112 is oscillatably mounted on a relatively short shaft 114 opposite ends of which are fixed in rearwardly extending portions of the support brackets 23 and 24. The opposite end of the lever 112 carries a roller 116 riding in the cam raceway of a drop wire actuating cam 120 having a high cam portion 120a and a low cam portion 120b.

With rotation of the main drive shaft 15, rotation will be imparted to the reed motion shaft 18 through the meshing gears 16 and 17 so that the reed motion shaft 18 will make one complete revolution with each three revolutions of the crank shaft 14. It is apparent, by referring to Figures 5 and 6, that the first pick or beat-up stroke of the lay 12 will be made with the terry slackening apparatus and roller carried by the lever arm 74 in the low portion 75b as shown in Figure 6 and by the time that the roller on the lever 74 reaches the high portion 75a of the cam 75, the roller 116 on the lever 112 will have moved onto the high portion 120a of the cam 120 so that the plate 80 will be in the raised position shown in Figure 7. Thus, the bank 50 of drop wires 49 will be supported by the plate 80 when the terry warp threads T are slackened by movement of the roller on the cam lever 74 moving onto the high portion 75a of the cam 75.

It is also apparent by referring to Figures 5 and 6 that the lever 74 will be lowered and raised by the high portion 75a of the cam 75 during the time that the roller 116 on the lever 112 engages the high portion 120a of the cam 120. It should also be apparent that since control of the terry slackening mechanism and

control of the drop wire support plate 80 are entirely separate from each other, the time these two mechanisms operate may be varied by merely rotating the cams 75 and 120 relative to each other to obtain the desired timing.

With the cams 75 and 120 positioned in relation to each other as shown in Figures 5 and 6, it is apparent that with rotation of the shaft 18, the plate 80 will first be raised to render the drop wires in the bank 50 inoperative before the terry motion lever 71 is raised to rack the rollers 61 and 62 and slacken the terry threads T. The shape of the cam 120 will cause the plate 80 to remain in raised position, rendering the drop wires 49 in the bank 50 inoperative, for a short time following the completion of the terry warp slackening operation.

With the actuating linkage operatively connecting the plate 80 with the cam 120, it is apparent that any movement imparted to the lever 112 by movement of the roller 116 will be simultaneously imparted to both of the levers 96 and 97 and thus raise both vertical shafts 85 and 86 simultaneously so that the plate 80 will be raised in a level manner throughout its length. Thus, all of the drop wires 49 of the bank 50 will be raised equal amounts and at the same time. It is also an advantage to have the plate 80 moving upwardly in alinement with the longitudinal position of the drop wires 49 rather than have the plate raised in an arc as has heretofore been done because a vertically moving plate 80 will raise the drop wires 49 in a straight line so that they do not engage the guide bars 45 and there will be no rubbing or wear between the lower ends of the drop wires 49 and the plate 80 as it is raised.

It is thus seen that a stop motion for terry weave looms has been provided wherein the control means for slackening the terry warp during the terry beat-up strokes of the lay and the control means for rendering the bank of terry warp drop wires inoperative during the slackening of the terry warp are completely separate from each other and controlled by separate cam means fixed on a common shaft. The operating cams for each operation are adjustable relative to each other to provide means for varying the time of operation of the terry warp slackening means and the time of operation of the drop wire plate to render the drop wires inoperative.

In the drawings and specification there has been set forth a preferred embodiment of the invention and, although specific terms are employed, they are used in a generic and descriptive sense only and not for purposes of limitation, the scope of the invention being defined in the claims.

I claim:

1. In a pile loom for weaving terry cloth or the like having a terry warp, a bank of drop wires at times supported by the terry warp, means to stop the loom when any drop wire of said bank is not supported, and a shaft driven in timed relation to operation of the loom, the combination therewith of terry warp slackening means for intermittently slackening said terry warp, first cam means carried by said shaft and operatively connected to said terry warp slackening means to at times actuate the same, a drop wire supporting plate positioned below said bank of drop wires, and second cam means carried by said shaft and operatively connected to said plate to move the same into engagement with said drop wires for supporting said drop wires, said drop wire supporting plate being movable in a straight vertical path beneath said bank of drop wires.

2. In a loom for weaving terry cloth or the like having a terry warp, a bank of drop wires at times supported by the terry warp, terry warp slackening means to intermittently slacken said terry warp, first cam means operatively connected to said terry warp slackening means, and drop wire supporting means positioned beneath said

bank of drop wires and intermittently movable into and out of engagement with said drop wires to support said drop wires, said drop wire supporting means comprising a vertically movable drop wire supporting plate positioned beneath said bank of drop wires, guide means at each end of said plate for guiding said plate in straight vertical movement, and second cam means operatively connected to said guide means to raise and lower said plate in timed relation to operation of said loom and independently of operation of said first cam means.

3. In a loom for weaving terry cloth or the like having a terry warp, a bank of drop wires at times supported by the terry warp, terry warp slackening means to intermittently slacken said terry warp, first cam means operatively connected to said terry warp slackening means, and drop wire supporting means positioned beneath said bank of drop wires and intermittently movable into and out of engagement with said drop wires to support said drop wires, said drop wire supporting means comprising a vertically movable drop wire supporting plate positioned beneath said bank of drop wires, a guide shaft supporting each end of said plate, guide means carried by said loom for guiding said guide shafts and plate in straight vertical movement, a control shaft rotatably carried by said loom, a lever arm fixed adjacent each end of said control shaft and engaging said guide shafts, and second cam means operatively connected to said control shaft to intermittently oscillate said shaft to thereby raise and lower said plate in timed relation to operation of said loom and independently of operation of said first cam means.

4. In a loom for weaving terry cloth or the like having a reed motion shaft driven in timed relation to said loom, a terry warp, a bank of drop wires at times supported by the terry warp, terry warp slackening means to intermittently slacken said terry warp, first cam means mounted on said reed motion shaft and operatively connected to said terry warp slackening means, and drop wire supporting means positioned beneath said bank of drop wires and intermittently movable into and out of engagement with said drop wires to support said drop wires, said drop wire supporting means comprising a vertically movable drop wire supporting plate positioned beneath said bank of drop wires, guide means at each end of said plate for guiding said plate in straight vertical movement, and second cam means mounted on said reed motion shaft and operatively connected to said guide means to raise and lower said plate in timed relation to operation of said loom and independently of operation of said first cam means.

5. In a loom for weaving terry cloth or the like having a reed motion shaft driven in timed relation to said loom, a terry warp, a bank of drop wires at times supported by the terry warp, terry warp slackening means to intermittently slacken said terry warp, first cam means mounted on said reed motion shaft and operatively connected to said terry warp slackening means, and drop wire supporting means positioned beneath said bank of drop wires and intermittently movable into and out of engagement with said drop wires to support said drop wires, said drop wire supporting means comprising a vertically movable drop wire supporting plate positioned beneath said bank of drop wires, a guide shaft supporting each end of said plate, guide means carried by said loom for guiding said guide shaft and plate in straight vertical movement, a control shaft rotatably carried by said loom, a lever arm fixed adjacent each end of said control shaft and engaging corresponding guide shafts, and second cam means mounted on said reed motion shaft and operatively connected to said control shaft to intermittently oscillate said shaft to thereby raise and lower said plate in timed relation to operation of said loom and independently of operation of said first cam means.

6. In a loom for weaving terry cloth or the like having a reed motion shaft driven in timed relation to said loom,

a terry warp, a bank of drop wires at times supported by the terry warp, terry warp slackening means to intermittently slacken said terry warp, first cam means mounted on said reed motion shaft and operatively connected to said terry warp slackening means, and drop wire supporting means positioned beneath said bank of drop wires and intermittently movable into and out of engagement with said drop wires to support said drop wires, said drop wire supporting means comprising a vertically movable drop wire supporting plate positioned beneath said bank of drop wires, a guide shaft supporting each end of said plate, guide means carried by said loom for guiding said guide shaft and plate in straight vertical movement, a control shaft rotatably carried by said loom, a lever arm fixed adjacent each end of said control shaft

10
5
15

and engaging corresponding guide shafts, a control arm fixed at one end intermediate the ends of said control shaft, and second cam means mounted on said reed motion shaft and operatively connected to the other end of said control arm to intermittently oscillate said shaft to thereby raise and lower said plate in timed relation to operation of said loom and independently of operation of said first cam means.
